UNITED STATES PATENT OFFICE.

SVEN T. NELSON, OF MICHIGAN CITY, INDIANA, ASSIGNOR TO SULLIVAN MACHINERY COMPANY, A CORPORATION OF MASSACHUSETTS.

FORGING MACHINE.

Application filed December 19, 1925. Serial No. 76,538.

While this invention relates generally to improvements in forging machines, it is directed more particularly to a drill steel punching mechanism.

As is well known, drill steels are often provided with a small hole or bore extending throughout their length and during forging of the bit on the steel the opening becomes narrowed or is closed. It is an object of my invention to provide improved means whereby this hole may be reopened which means is particularly adapted to include as certain of its elements standard commercial mechanisms such as the actuating motor. The hole forming means constitutes generally three elements, namely, the hole opening punch, a motor preferably of the pneumatic type, and means actuated by the motor for imparting an impact to the punch both during insertion and withdrawal of the punch from the drill steel hole. A further object of the invention is to provide improved impact means whereby the same is completely operative from only one end of the actuating motor and to have such means so arranged that impact stresses are not transmitted through any of the motor mechanism as far as it can possibly be eliminated. A further object is to provide improved means whereby when the punch has completed its hole opening operation the impact forces may be imparted thereto in a rearward direction merely by the reverse movement of a hand operated feed lever, although it will be clear that any other sort of mechanism could be used for causing the impact forces to be imparted in either direction of punch movement.

In the accompanying drawings I have shown for purposes of illustration one form which my invention may assume in practice.

In these drawings,—

Fig. 2 is a vertical longitudinal sectional view.

Fig. 3 is a sectional detail view showing a modified form of means for imparting an impact to the drill punch.

In the illustrative embodiment of my invention I have shown a fragmentary portion of a usual type of supporting frame 1 having a suitable stationary clamping jaw 2 and a cooperating movable jaw 3 adapted to clamp a drill steel 4 which has a hole 5 to be opened. The frame 1 is provided with parallel guideways 6 within which are slid-

ably mounted guide portions 7 carried by a motor casing 8. The motor is of a usual reciprocating type having a piston 9 provided with a forwardly projecting piston rod 10 which extends through a usual cylinder head 11. The piston is actuated by any suitable power medium which is controlled by any usual type of valve mechanism. Also slidably guided by the guideways 6 is anvil mechanism for transmitting impacts to a punch and comprises a base plate 12 having laterally extending portions 12^a receivable in the guideways 6. A portion 13 projects upwardly from the front end of the base 12 and has a cylindrical boss 14 projecting forwardly therefrom. An opening 15 provided in the boss receives the shank 16 of the punch 17. A collar 19 formed on and adjacent the punch shank 16 is clamped between the boss 14 and a collar 18, the latter having threaded engagement with the boss 14; and as a result, the punch 17 is firmly secured within the opening 15. Projecting upwardly from the rear end of the base 12 is an impact portion 20 having a semi-cylindrical recess 21 while a removable cap 22 is secured to the portion 20 as by screws 23, this cap having a cylindrical recess 22^a adapted when mated with the lower recess to form a cylindrical opening through which the piston rod 10 may extend.

To impart an impact to the anvil mechanism by the motor, a hammer element 24 is formed on the outer end of the piston rod 10. This hammer may be made integral with the piston rod or removably secured thereto in any suitable and well known manner. Means for insuring successive impact blows in one direction upon the punch comprises a hand lever 25 pivotally secured to the frame and having an arm 26 to which is pivotally secured a link 27 in turn connected to the motor casing in any suitable manner as at 28.

In the operation of this form of the device, the steel will first be clamped, whereupon power flow to the motor will cause reciprocation of the hammer 24 and by pressing the hand lever 25 downwardly the motor will be fed forwardly to cause the hammer 24 to be brought in striking range of the portion 13 of the anvil mechanism. The distance between the portions 20 and 13 is slightly greater than the combined stroke of the piston 9 and width of the hammer. 110

Accordingly as long as the hand lever 25 is depressed the hammer 24 will strike only the portion 13. When the punch has been driven the desired distance into the steel the operator by pulling upwardly on the hand lever and thereby causing reverse movement of the motor casing 8 will cause the hammer 24 to strike only the rear portion 20 and thereby drive the punch from the hole. In Fig. 3 I have shown the piston rod provided with two hammer elements 24^a and 24^b.

From the above described structure it will be seen that I have provided an extremely simple means whereby the elements which are subjected to the hardest wear will always be open to immediate inspection and can be replaced in a relatively short time as it is only necessary to remove the upper portion 22 and slide the anvil mechanism from the guideways 6. It is to be noted also that no impact stresses are imparted to the punch through the motor casing or any of its auxiliary devices.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A drill steel punch comprising the combination of a motor, anvil mechanism disposed at one end of said motor having a plurality of anvil surfaces, a hole forming tool associated with said anvil mechanism, and means actuated by said motor and movable between said anvil surfaces for imparting to the latter blows to drive the tool in opposite directions.

2. A drill steel hole opening mechanism comprising the combination of a motor, anvil mechanism located on only one side of said motor, a hole forming tool having operative connection with said mechanism, a hammer actuated by said motor, and means whereby said hammer is adapted to strike a series of blows on said anvil mechanism in opposite directions, said anvil mechanism including a member having opposed hammer engaging surfaces between which said hammer reciprocates.

3. A drill steel hole opening mechanism comprising the combination of a motor, a hole opening tool, a hammer actuated by said motor, and anvil means cooperating with said hammer to drive said tool in opposite directions, said anvil including a pair of cooperating anvil surfaces one of which has a longitudinal opening through which said hammer reciprocates and means for causing

said hammer to strike a series of blows on said anvil in only one direction at a time.

4. A drill steel hole opening mechanism comprising the combination of a movably mounted motor, a hole opening tool, a movably mounted anvil mechanism for transmitting impacts to hammer said tool in opposite directions, said anvil mechanism being disposed entirely at one end of said motor, a hammer element actuated by said motor and cooperating with said anvil, and means for effecting relative movement between said motor and anvil at will to change the direction of hammering.

5. A drill steel hole opening mechanism comprising the combination of a motor having a piston and a hammer element actuated thereby, a movably supported hole opening tool, a movably supported anvil mechanism associated with said tool and having opposed anvil surfaces located on the same side of the piston head and spaced a distance greater than the piston stroke, and means connecting said piston and anvil whereby said hammer element is disposed between said surfaces.

6. A drill steel hole opening mechanism comprising the combination of a motor having a reciprocable piston, a hammer actuated thereby, and an anvil having opposed hammer engaging surfaces between which said hammer is positioned, said surfaces being on the same side of the piston head but spaced so that even during a maximum stroke of said piston said hammer is adapted to engage only one of said anvil surfaces at a time.

7. A drill steel hole forming mechanism comprising the combination of a motor having a piston rod carrying a hammer element, an anvil disposed at only one end of said motor, a hole opening tool associated with said anvil, means for imparting a series of blows by said hammer element to said anvil in opposite directions, and means for moving said motor and anvil in only one direction at a time to insure hammering of said punch in only one direction at a time.

8. A drill steel hole forming mechanism comprising the combination of a frame having guideways, a motor slidably mounted therein and having a piston rod carrying a hammer element at only one end of said motor, an anvil comprising a substantially U-shaped member also slidably mounted in said guideways and adapted to be actuated in opposite directions by said hammer element, and a hole opening tool carried by said anvil mechanism.

9. A drill steel hole forming mechanism comprising the combination of a hole forming tool, a hammering motor, an anvil mechanism separate from the hammering motor and disposed only on the side of the motor towards the tool and slidably toward

or from said motor, said hammering motor and anvil mechanism cooperating to hammer said tool in opposite directions at will, and means for bodily moving said motor to 5 control the direction of the hammering action.

10. A drill steel hole opening mechanism comprising a support, a hammering motor carried thereby and comprising a reciprocable hammer element adapted to strike a series of blows, a hole opening tool, and an

anvil associated with said tool, said anvil being carried by said support so as to receive repeated blows from the hammer element of said hammering motor and to 15 move on said support relative to said hammering motor during hammering of said tool, said anvil being disposed only on the side of the motor toward the tool.

In testimony whereof I affix my signature. 20

SVEN T. NELSON.

CERTIFICATE OF CORRECTION.

Patent No. 1,680,254.

Granted August 7, 1928, to

SVEN T. NELSON.

It is hereby certified that error appears in the printed specification of the above numbered patent requiring correction as follows: Page 1, between lines 42 and 43, insert the words "Fig. 1 is a plan view"; and that the said Letters Patent should be read with this correction therein that the same may conform to the record of the case in the Patent Office.

Signed and sealed this 25th day of September, A. D. 1928.

(Seal)

M. J. Moore,
Acting Commissioner of Patents.
